UNITED STATES PATENT OFFICE.

BERT R. WILLIAMSON, OF FAIRFIELD, MAINE, ASSIGNOR TO KEYES FIBRE COMPANY,
OF WATERVILLE, MAINE, A CORPORATION OF MAINE.

MOLD FOR APPARATUS FOR MOLDING PULP ARTICLES.

Specification of Letters Patent. Patented Jan. 4, 1921.

1,364,228.

Application filed October 16, 1919. Serial No. 331,100.

To all whom it may concern:

Be it known that I, BERT R. WILLIAMSON, a citizen of the United States, residing at Fairfield, county of Somerset, State of Maine, have invented an Improvement in 5 Mold for Apparatus for Molding Pulp Articles, of which the following description, in connection with the accompanying drawing, is a specification, like characters on the drawing representing like parts.

10 This invention relates to a mold to be used in the formation of articles such for example as pie plates and butter dishes from liquid pulp. Molds of this general character are employed in apparatus such as 15 shown in the patent to Keyes No. 759,616 granted May 10, 1904. Such a mold is composed of two hollow members, these members being connected to sources of vacuum 20 and compressed air. When the mold members are separated, one or both pass through a vat of liquid pulp and a thin layer of pulp is sucked on to the face of the immersed member or members. After the mold members have passed out from the vat of pulp 25 they are closed together and pressure applied. Subsequently the molded layer of pulp then in the form of the desired article is removed and dried.

30 It is obviously important that the pulp article, then in a soft and moist condition shall be readily removable from the mold members without injury, otherwise the article is spoiled. It is also desirable that the 35 faces of the article, but particularly the inner face if it be a container shall be of a smooth and finished character. Heretofore in order to secure these results it has been necessary to employ a brass wire screen or 40 finely reticulated brass screen over the perforated face of the metal mold member in order to enable the pulp layer to be readily removable therefrom without injury, otherwise the moist pulp layer would stick or 45 cling to the metal of the mold member which has been of iron or brass; and it has also been necessary to use such a screen in order to produce the desired finished character of surface.

50 I have discovered that a mold member made of aluminum will not stick or cling to the moist layer of pulp. I have discovered that aluminum presents a surface of a peculiar character which is substantially 55 non-adherent to moist pulp. Hence, I find

that it is only necessary to use a screen over the perforated face of an aluminum mold member if it is desired to get that character of finish on the pulp article which a screen will produce.

60 This invention therefore consists in providing an aluminum mold member for use in forming articles from liquid pulp having an exterior pulp engaging face perforated to communicate with the chamber at the 65 back of the mold.

The invention also consists in providing such an aluminum mold member with a finely reticulated metal screen overlying its 70 perforated face to form the pulp contacting surface when it is desired to get the particular finish imparted by such a screen.

75 These and other objects and features of the invention will appear more fully from the accompanying description and drawing, and will be particularly pointed out in the claims.

80 The drawings illustrate a mold of a design suitable for application to an apparatus of the type disclosed in the patent to Keyes above referred to.

In the drawings—

85 Figure 1 is a view chiefly in central vertical section of the complete mold and its supports.

Fig. 2 is an elevation looking at the interior of the concave surface of the female 90 mold member.

In the construction illustrated one mold member is supported by an arm 1 forming a part of the apparatus while the other mold member is supported by an arm 2 which may be moved toward and from the arm 1 to effect the separation and closing 95 together of the mold members.

90 The end of the arm 1 is provided with a hollow head 3 having a flat surface 4 to which the mold member is clamped. This hollow head 3 is in communication with suitable sources of vacuum and compressed air. 100 The outer end of the arm 2 likewise is provided with a hollow head 5 having a flat surface 6 to which the other mold member is clamped and this hollow head is likewise in communication with suitable sources of 105 vacuum and compressed air.

110 The mold members may be of any suitable form or shape depending upon the article to be formed and in the illustrated construction are of a shape to form a butter

dish. The male mold member 7 is shaped at its exterior face to correspond with the interior of the article and is clamped rigidly to the hollow head 3. This mold member 7 is hollow to communicate with a hollow head and is provided with a plurality of perforations 8 extending from its face to the hollow interior. This mold member 7 is formed of aluminum and cast into the required shape. When, as here, it is to form the interior or finished face of the article it is usually desirable that it be covered with a finely reticulated metal screen such as the brass wire screen 9 illustrated, and this screen is shown clamped in place by an annular clamping plate 10 fitting over the outer flange of the mold member 7. The other mold member 11 is also formed of aluminum and is cast into the desired form to correspond with the other face of the article to be molded. This mold 11 is also provided with a plurality of perforations 12 extending from its face to the hollow at the back which may be partially or entirely in the hollow head 5. In the form shown the mold member 11 forms the unfinished side of the article and hence no metal screen is necessary.

The metal screen in either case is only necessary where it is required to form a particular finish on the article. I find that, as above pointed out, the surface of the metal aluminum presents what may be termed a greasy finish or in other words, is of such a character that it is non-adherent to the moist pulp so that the molded article

while still moist is readily removable from the aluminum surface of the mold without clinging or sticking thereto.

The aluminum mold members have the further advantage that they are light in weight, thus reducing the power required to operate the apparatus.

The aluminum mold members also have the further advantage that they are not subject to corrosion by the action of the liquid pulp.

The invention thus presents a mold member and a mold which is of great practical advantage in a pulp molding apparatus in enabling the pulp articles to be readily, accurately, and speedily molded in a perfect condition.

Having thus described my invention what I claim as new and desire to secure by Letters Patent is—

1. A mold for pulp articles comprising a member having a perforated face, a finely reticulated metal screen overlying and secured to said face and forming the pulp contacting surface, and a complementary member of aluminum having a perforated face itself forming a non-adherent pulp contacting surface.

2. An aluminum mold member for use in forming articles from liquid pulp having an exterior non-adherent pulp engaging face perforated to communicate with the back of the member.

In testimony whereof, I have signed my name to this specification.

BERT R. WILLIAMSON.
